GOLF TEE

William C. Miller, 900 MacQueen Blvd.,
St. Albans, W. Va.

Filed July 13, 1959, Ser. No. 56,759

Term of patent 14 years

(Cl. D34—5)

Fig. 1 is a perspective view of a golf tee embodying the design;

Fig. 2 is a side elevational view of the golf tee;

Fig. 3 is a longitudinal sectional view of the golf tee; and

Fig. 4 is a plan view of the golf tee.

A characteristic feature of the design is the combination of the ball-receiving cup having a height substantially less than its diameter, with the stem and intermediate flange which protrude outwardly from the base of the cup a distance substantially equal to the height of the cup, all as shown.

I claim:

The ornamental design for a golf tee, substantially as shown and described.
